UNITED STATES PATENT OFFICE.

MELANCTHON HANFORD, OF BOSTON, MASSACHUSETTS.

IMPROVEMENT IN ELEVATORS.

Specification forming part of Letters Patent No. 124,952, dated March 26, 1872.

To all to whom these presents shall come:

Be it known that I, MELANCTHON HANFORD, of Boston, in the county of Suffolk and Commonwealth of Massachusetts, have made an invention of certain new and useful Improvements in Elevators; and do hereby declare the following to be a full, clear, and exact description thereof, due reference being had to the accompanying drawing making part of this specification, and in which—

Figure 1 is a plan, and Fig. 2 a vertical and longitudinal section of my invention, while Fig. 3 is a vertical section of the cylinders and drip-cup to be explained.

I have, in this invention, made provision whereby to distribute and equalize the draft or labor devolving upon two or more hoisting ropes of an elevator-carriage, and incidentally to relieve the jar and thrusts resulting to the carriage under ordinary usage, and especially in the event of breakage of one or more of said ropes. My present invention consists in the employment, in combination with each rope or suspensory of an elevator-carriage where two or more ropes are employed, of a plunger traversing a well or cylinder, the lower end of the rope being attached to the plunger, and a supply of oil being deposited within the cylinder and over the plunger to interpose a cushion to relieve the concussion and thrusts upon the carriage and ropes, and to obviate the trembling motion often experienced.

In carrying into practice my invention, I obtain a pair of upright cylinders, A A, cast in one piece of metal and bolted in a secure manner to the central roof beam of the elevator carriage. Within each cylinder and standing ordinarily about midway thereof, I dispose a plunger, b, the rod, c of which rises through the cap or head, d of said cylinder, or a stuffing-box, e, applied thereto to prevent escape of oil. Within each cylinder and over the plunger contained in it, I pour a sufficient quantity of oil or other proper oleaginous matter to fill or about fill the space intervening between the top of the plunger and the cap-plate of the cylinder, a free communication being had between the two cylinders, as shown by the cross-passage, f in the drawing, in order to insure an equilibrium of pressure upon the body of oil contained in them. The bottom of

each cylinder is perforated with an orifice, g, which serves as an air-vent to relieve the vacuum which would otherwise exist below the plunger, and to permit of escape of any minute quantity of oil which may escape between the plunger and cylinder. This latter contingency is a remote one, as the plunger fits or should fit so tightly within the cylinder as to render escape of oil impossible. A suitable drip-cup, H, is placed below the orifice, g to arrest any oil which may escape by way of such orifice. It will be apparent that, by means of the cylinders, A A and pistons or plunger, b, in combination with the ropes, as explained, the draft upon the rope is equalized and an equilibrium established which is productive of very beneficial results, while the oil or its equivalent serves as a cushion to relieve the carriage and ropes from the effects of any jerking or thrusts upon the latter.

The advantages of my improvement will be especially apparent on breaking of one of the ropes which actuate the carriage, as in this event the labor devolving upon the fractured rope is borne by and distributed equally and generally throughout the remaining ropes, and this distribution and disposition of labor is brought about gradually, owing to the length of time required for the oil to pass through the oil-passage, f, which it must do as it is displaced by the release and fall of the plunger belonging to the fractured rope and the corresponding ascent of the other plungers.

Although I have shown in the present instance one pair of ropes, cylinders, and plungers, it has been for the purpose of illustrating the nature and purposes of my invention. In practice I shall usually employ four ropes, and in some cases may adopt even more.

I claim—

The cylinders, a a and plungers, b, as applied to an elevator-carriage and connecting with the hoisting ropes thereof, such cylinders having open communication each with the other at top, and the orifices, g at bottom, and provided with a quantity of oil or its equivalent, the whole being for purposes stated.

MELANCTHON HANFORD.
